UNITED STATES PATENT OFFICE.

HENRY C. P. WEBER, OF EDGEWOOD PARK, PENNSYLVANIA, ASSIGNOR TO WESTINGHOUSE ELECTRIC & MANUFACTURING COMPANY, A CORPORATION OF PENNSYLVANIA.

FRACTIONATING COLUMN.

Application filed August 5, 1919. Serial No. 315,502.

To all whom it may concern:

Be it known that I, HENRY C. P. WEBER, a citizen of the United States, and a resident of Edgewood Park, in the county of

5 Allegheny and State of Pennsylvania, have invented a new and useful Improvement in Fractionating Columns, of which the following is a specification.

My invention relates to fractionating 10 columns and it has, for its primary object the provision of a device of the above indicated character which shall be simple in construction and, at the same time, unusually effective in operation.

15 A further object of my invention is to provide a fractionating column or condenser by means of which the vapor to be condensed, previous to its condensation, is washed by passage through a liquid consisting of the more readily condensable portions of the distillate or vapors. This may be introduced into the apparatus initially or it may accumulate of itself during the first part of the distillation.

20 Another object which I have in view is to provide a condenser with a jacketing by means of which the temperature at which the condenser operates may be controlled.

This jacketing is filled with a suitable 25 liquid which, if left to itself, reaches a temperature slightly below that at which the fractionating column is operating. This provides a surrounding field of uniform temperature about the inner portion, thus insuring greater uniformity of separation.

30 In this connection, the construction of my fractionating column is such that, if the controlling liquid in the jacket has a constant boiling point, which may be substantially that of one of the constituents to be separated, a perfectly uniform temperature will be maintained in the wash liquid so as to insure absolute uniformity of separation of the liquids being distilled.

40 Another advantage of this construction resides in the fact that, by employing a circulation of cooling liquid in the jacketing of the condenser, the condenser may be employed as a reflux condenser.

45 With these and other objects in view, my invention will be more fully described, il-

lustrated in the drawings, in the several views of which corresponding numerals indicate like parts, and then particularly pointed out in the claims.

55

In the drawings Fig. 1 is a vertical, central, sectional view of a simple form of fractionating column or condenser constructed in accordance with my invention; Fig. 2 is a transverse section, taken on the line 60 II-II of Fig. 1, and Fig. 3 is a section corresponding to Fig. 1 and disclosing another embodiment of my invention.

Figs. 1 and 2 disclose one of the simplest forms of my invention which may comprise 65 a tubular body 1 open at its ends and formed intermediate its length with an enlargement providing a condensing chamber 2. An annular flange or baffle 3, preferably formed integrally with the top wall of the chamber, 70 depends in spaced relation to the peripheral wall thereof and projects, at its lower edge, below the level of the upper edge of the spaced, surrounding wall of a cup 4.

The cup 4 may be supported, both in 75 spaced relation to the bottom wall of the chamber 2 and to the flange 3, by any suitable means. For example, if the apparatus is of glass, as is customary in columns of this character, the wall of the cup, at intervals, may be fused and pressed into sealing engagement with the flange, as indicated at 80 5. Preferably, the bottom of the cup will be provided centrally with a depending projection 6, for a purpose which will be later 85 pointed out. A discharge tube 7 leads from the portion of the tubular body 1 above the chamber 2 and is preferably directed upwardly and then downwardly, as shown in Fig. 1.

90 When employing the fractionating column or condenser shown in Figs. 1 and 2, the lower end of the tube 1 may be connected to a still of any suitable character, while the branch tube 7 may be connected to a 95 suitable receiving vessel. A stopper, through which a thermometer has been extended, may then be utilized to close the upper end of the tube 1 to prevent escape of the vapors and to indicate the temperature in the device.

100 As the mixed vapors of the liquids of

different boiling points enter the chamber 2, the liquid of the higher boiling point will be condensed first and will gather in the cup 4 to provide a liquid seal between the 5 lower and upper portions of the tubular body 1. Under these circumstances, it will be apparent that the vapor of the liquid having the lower boiling point must pass through, and be washed by, the liquid contained in the cup before it can pass to the 10 branch tube 7. This insures an extremely effective separation of the liquids. As the quantity of liquid in the cup 4 increases, it will gradually overflow the cup and drip 15 from the projection 6 from which it will fall axially of the tubular body 1 so that it will not gather upon the walls thereof, or materially interfere with the upward passage of vapors.

20 In Fig. 3 I have illustrated a preferred form of condenser or fractionating column in which the tubular body 7' may be formed with a plurality of spaced condensing chambers 8, each provided with its depending annular baffle 9 supporting a cup 10. As each of these chambers and its baffle and supported cup are identical with the corresponding parts of the device shown in Figs. 1 and 2, a detailed description is not necessary.

25 A jacketing 11 may surround all of the chambers 8, being spaced therefrom to permit circulation of a controlling fluid about the chamber, the jacketing, of course, being sealed to the body 7' above and below the 30 chambers. This jacketing may be provided, near its lower end, with an inlet tube 12 and, near its upper end, with an outlet tube 13 to permit circulation of a controlling fluid about the chambers 8. A branch pipe 14, 35 of course leads from the tubular body 7' above the jacketing and corresponds to the tube 7 of the condenser first described.

The operation of the fractionating column or condenser shown in Fig. 3 is, in 40 principle, the same as that shown in Figs. 1 and 2. Vapors of as many different boiling points as there are chambers 8 and cups 10 may, however, be separated from a mixture 45 of vapors of various liquids during their passage through the condenser.

The main difference between this apparatus and the one first described, however, resides in the utilization of the jacketing 11. For example, a liquid may be circulated 50 through this jacketing at a temperature substantially the same as the boiling point of the lowest boiling point liquid of the mixture of liquids being distilled so that the liquids in the cups serving as wash liquids 55 for the vapors passing through the column may be kept near their boiling temperatures. This permits the employment of the device with high-boiling-point liquids, such as 60 gums and resins which might otherwise

solidify in the cups and prevent the passage 65 of vapors of lower boiling-point liquids.

On the other hand, if a cooling liquid, of suitable character, is circulated through the jacketing, the apparatus may be employed as a reflux condenser, all vapors entering it being 70 condensed in one or more of the cups and from them returning to the still. Other methods of employing my fractionating column or condenser will readily occur to those skilled in the art.

75 As an example of its efficiency, an apparatus of this character was employed in distilling a 50% mixture of alcohol and water and it was found that, when three-fifths of the mixture had been boiled off, all of the alcohol 80 had been removed and condensed. No other condenser known to me is capable of doing this.

85 Although I have illustrated several embodiments of my invention and described it in considerable detail, it will be apparent that my invention is susceptible of various changes. For this reason, no limitations are to be imposed upon my invention other than 90 those indicated in the claims.

95 I claim as my invention:—

1. A fractionating column comprising a tubular body provided, in its length, with a condensing chamber and means disposed in the chamber providing for a liquid seal between the ends of the body including a cup, and a depending projection thereon.

100 2. A fractionating column comprising a tubular body provided, in its length, with a condensation chamber, an annular, depending, baffle flange in the chamber and a condensation cup having a projection thereon surrounding and spaced from the lower portion of the flange and supported thereby.

105 3. A fractionating column comprising a tubular body provided, in its length, with a condensing chamber, an annular flange depending from the wall of the chamber and in axial alignment with the tubular body and a condensing cup supported by the flange and surrounding the lower end thereof.

110 4. A fractionating column comprising a tubular body provided, in its length, with a condensing chamber, an annular flange depending from the upper wall of the chamber and centrally thereof, a cup supported by the flange and surrounding the lower end thereof, in spaced relation thereto, and a jacketing surrounding the chamber.

115 5. A fractionating column comprising a tubular body provided, in its length, with a plurality of condensing chambers, and means disposed in each chamber providing for a liquid seal between the ends of the body including a cup, and a depending projection thereon.

120 6. A fractionating column comprising a tubular body provided, in its length, with a

plurality of enlargements forming condensing chambers, annular depending flanges supported by the upper walls of the condensing chambers, cups supported by the flanges and surrounding the lower ends thereof in spaced relation thereto to provide for liquid seals, a jacketing, providing for circulation

of a fluid, surrounding the chambers and a branch tube leading from the body above the jacketing.

10

In testimony whereof, I have hereunto subscribed my name this 31st day of July, 1919.

HENRY C. P. WEBER.
